VALVED CLOSURE PLUG FOR INSERTION
IN THE NECK OF A BOTTLE

Seymour Breakstone, Chicago, Ill.

Application April 15, 1946, Serial No. 662,351

1 Claim. (Cl. 215—47)

1

This invention relates to devices for aerating and dispensing whipping cream.

It is customary to produce whipped cream by dispensing whipping cream under pressure through a rather fine nozzle. Liquid whipping cream is placed into a container and the head space above the whipping cream is filled with gas under appropriate pressure. The liquid cream is adapted to be discharged into the atmosphere through a nozzle. When this occurs the cream becomes aerated and in effect whipped as it leaves the nozzle.

It is one of the objects of the present invention to provide a dispenser suitable for whipping cream which dispenser has a self-sealing closure valve through which may be injected a filling tube for placing into the container either the whipped cream or gas under pressure, or both, and which may then be removed and leave the container sealed and under pressure, the arrangement being such that a valve nozzle may thereafter be inserted through the bottle cap for facilitating the discharge of the liquid contents. It is one of the objects of the present invention to provide an improved closure cap for bottles of the above mentioned character. It is a still further object of the present invention to provide an improved shut-off valve for bottles of the above mentioned character.

The attainment of the above and further objects of the present invention will be apparent from the following detailed description taken in conjunction with the accompanying drawing, in which

Figure 1 is a top view of a container embodying the present invention;

Figure 2 is a longitudinal sectional view through the container;

Figure 3 is a fragmentary top view of the container with a dispensing valve in place; and

Figure 4 is a bottom view of the closure cap.

The present invention is particularly designed for the provision of appropriate containers which may be properly filled at a distance from the ultimate user, transported to him in any suitable manner, and then be stored on ice until the time of use. At the desired time the user may insert a dispensing valve through the closure into the container and use as desired. As such use may be in the home, with all the contents not being used at one time, provision has been made so that the dispensing valve may be removed for cleaning, etc., while the unused contents may again be stored on ice.

Referring to Figure 2, a glass bottle or contain-

2

er 11 has been provided, glass being preferable in order that the user may ascertain readily the amount of contents on hand. The bottle is provided with a hollow neck terminating in an opening surrounded by a lip 12. A metal closure cap, of the "crown cap" type, indicated generally as 12, is utilized on the top of the bottle 11, being provided with the usual crimped edge 13 to allow easy removal from the bottle.

10 The metal cap 12 has a rubber insert 14 which is secured to the inside of the cap and which has a projecting portion 16 which extends within the neck of the bottle 11 and fits tightly therein. The extremity of the insert 14 is formed of a projecting portion 17 having a smaller diameter than the portion 16.

15 The metal cap 12 is provided at the center thereof with a small circular opening 18. The insert 14 is provided with an aligning circular opening 19 which extends only partly through the projecting portion 16, the opening 19 terminating in a self-closing valve comprising straight line cut or slit 21 extending through the remainder of the portion 16 and through the portion 17.

20 25 In use, a closing cap 12 is capped on the top of a clean sterilized bottle 11. Thereafter a filling tube may be inserted through the opening 18 in the cap 12, and through the opening 19 in the insert 14. By applying pressure to the filling tube it may be forced through the straight line cut or slit 21 in the projecting portions 16 and 17, the rubber expanding sufficiently to allow it to pass therethrough while making a sealing fit around the tube. The bottle may be partially filled with whipping cream to a suitable level 22 before the cap is applied, or through the filling tube after application of the cap. The remaining space 23 in the bottle is then filled with a suitable gas, such as nitrous oxide, under pressure, which is introduced through the filling tube. The filling tube may be withdrawn. The resilience of the rubber closes the straight line cut or slit 21 in the insert 14, with pressure exerted from within the bottle 11 on the side of the projecting portion 17 aiding such closure. The filled bottle may now be transported and stored until it is desired to use the contents thereof.

25 30 35 40 45 The contents are removed through an appropriate dispensing valve, indicated generally as 26 in Figure 3. The valve includes a cylindrical body portion 27 divided into two sections or chambers by a partition 28. A spout 29 extends from the upper section and a tube 31 from the lower section.

50 55 A plunger 34 having a stem portion 36 and a

larger diameter valve head 37 extends within the body portion 27, passing through suitable openings in the top and in the partition 28. A spring 38 normally urges the plunger 34 in an upward direction, thereby causing the top of the valve head 37 to engage the under side of the partition 28, forming a seal.

When it is desired to use the whipped cream, the tube 31 of the valve 26 is inserted through the opening 18 in the cap 12 and through the opening 19 in the insert 14. By the application of pressure the tube 31 may be pushed through the straight valve slit 21 in the portions 16 and 17, the rubber expanding, as was previously described. However, no pressure will escape at this time, as the plunger 34 will be in its upward position and the valve 32 will be closed. The bottle 11 may then be tilted or inverted, the spout 29 positioned lowermost. As finger pressure is applied to the plunger 34 the valve head 37 will be moved away from the under side of the partition 27, thus uncovering the opening in the partition 27. Whipping cream under pressure will now be forced through the tube 31, the opening in the partition 28 through which the stem 36 passes, and out of the spout 29. When the cream under pressure issues to the atmosphere it issues as "whipped" cream.

After a sufficient quantity of the contents has been dispensed the plunger 34 will be released and the bottle 11 returned to its original position. The valve head 37 will engage the under side of the partition 28 forming a seal.

The valve 26 may now be removed from the bottle 11, the rubber insert sealing itself upon removal of the tube 31, as was described previously. The bottle 11 may now be stored on ice for future use and the valve 26 may be washed to be in readiness for future use.

After the contents has all been used the cap 12 may be removed, by any suitable bottle opener. It may be reused or thrown away, or the rubber valve insert may be reused.

In compliance with the requirements of the patent statutes I have here shown and described a preferred embodiment of my invention. It is, however, to be understood that the invention

is not limited to the precise construction here shown, the same being merely illustrative of the principles of the invention. What I consider new and desire to secure by Letters Patent is:

A valved closure plug for insertion into the neck of a bottle, said plug comprising a yielding cylindrical rubber body having a peripheral flange at its upper end and having a substantially smaller diameter cylindrical projection at its lower end, a self closing slit extending through the cylindrical projection and into the body of the plug and extending through a substantial portion of the body of the plug above the projection and terminating at its top in an enlarged opening which opens at the top of the closure plug, the lower cylindrical projection at the bottom of the plug constituting a valve forcing the bottom of the slit radially inwardly to the closed position by the action of the pressure of the surrounding atmosphere when the pressure at the bottom of the plug is greater than the pressure at the top of the plug, the plug being solid above the cylindrical projection and the slit surfaces being in contact with each other in the part of the rubber body above the projection, whereby the rubber above the top of the projection prevents upward flexing of the rubber of the projection at the slit thereof.
